UNITED STATES PATENT OFFICE.

THOMAS C. P. TRELEAVEN, OF CHICAGO, ILLINOIS.

GAME APPARATUS.

1,290,414.

Specification of Letters Patent.

Patented Jan. 7, 1919.

Application filed September 7, 1918. Serial No. 252,998.

To all whom it may concern:

Be it known that I, THOMAS C. P. TRELEAVEN, a citizen of the United States, residing at Chicago, in the county of Cook and 5 State of Illinois, have invented certain new and useful Improvements in Game Apparatus, of which the following is a specification.

My invention relates to game apparatus.

One of the objects of my invention is to 10 provide an interesting educational game which requires the exercise of skill of the player for the successful manipulation of the instrumentalities provided for playing the game.

15 The game is illustrative of submarine activity and is adapted for two or more players. As many more persons as desired may engage in the game as partners or as independent players.

20 The board upon which the game is played is provided with four points from which a submarine shot may be fired at vessels at sea comprising an enemy transport having four barges in tow located somewhere near the 25 center of the board. These initiatory firing points are named for four of the capital cities of the respective allied countries, London, Paris, Rome and Washington, and the 30 flags of the allied nations, together with the flag of truce, are located on either side of the respective initiatory firing points. Representations of the North Sea, the English Channel, the Atlantic and Pacific Oceans cover the major part of the upper surface of 35 the board.

Extending under the water surface, from 40 each of the initiatory firing points is a conical channel upturned at its inner end and terminating in one of the enemy barges. A ball is fired through these channels, or 45 chambers and emerges at the opening in the respective barges and rolls down the surface of the board until it finally rests in a pocket or depression designated by a numerical reference of a given value. The 50 player recording the highest aggregate enumeration wins the game.

In the drawings:

Figure 1 is a plan view of the game board 55 or apparatus.

Fig. 2 is a section, taken on line 2—2 of Fig. 1.

Fig. 3 is a section taken on line 3—3 of Fig. 1.

55 Fig. 4 is an end view of one corner of the

board showing one of the initiatory firing points.

Fig. 5 is a section taken on line 5—5 of Fig. 1.

In all the views the same reference characters are employed to indicate similar parts.

The game board 10 may be made of plastic material, such as plaster of Paris or the like, or formed up of sheet metal, or made of wood or of any other material well adapted for the purpose. Located near the center of the board and at sea, is a transport 11, having in tow, barges 12, 13, 14 and 15. Radiating from the respective barges are the 70 initiatory firing points from which a shot may be fired, indicated by 16, representing Paris; 17, representing Rome; 18, representing Washington, and 19, representing London. The English Channel is designated by 75 20. 21 is the North Sea. 22 is the Pacific Ocean, and 23 represents the Atlantic Ocean. 24 is a depression or pocket to receive the ball within the English Channel. 25 is a 80 similar pocket in the North Sea. 26 is a pocket in the Pacific Ocean and 27 a pocket in the Atlantic Ocean. Each of the pockets designated has a certain numerical value, as indicated by the rules of the game 28. There are four life buoys symmetrically arranged, three of which are designated by the 85 reference characters 29 to 31 inclusive, consisting of pockets to receive the balls, which also have distinctive numerical values. The life buoy 32 is not shown in Fig. 1, being 90 above the part cut away showing the lower part thereof in section. 33 is the bell buoy and 34 to 41 inclusive are stations for the Belgian, French, English, Canadian, American, Japanese and Italian flags, including 95 the white flag of truce. Radiating from each of the four corners, 16 to 19 inclusive, are conical submarine, tapering channels 42, having a large outer opening 43 and a relatively small opening 44 at the inner end. 100 Each channel terminates in one of the barges 12 to 15 inclusive, respectively. The decks of the barges are removable and each consists of a flat plate or piece of cardboard covering the openings 44 and three of them 105 are designated by the numeral 45, 46, 47, respectively. The decks 46 and 47 are shown in place in Fig. 1, and the opening 44 is shown in the barge 15 with the deck removed. Near the larger outer terminal of 110

the conical chamber 42 is an elevation 50, upon which to place the ball, or shot 51. On either side of the opening 43 are pins 52 and 53, between which a rubber band 54 extends. Secured to the center portion of the rubber band 54 is a thumb and finger piece 56, having a projection 57 for striking the ball. To make a shot, the thumb piece is seized and the band is stretched outwardly and then released. The part 57 will strike the ball and drive it through the channel 42, raising the deck 45, if the player has sufficiently stretched the band. If he has not sufficiently stretched the band 54, the ball will not displace the deck 45, and will return from the channel 42 into the position shown at 58, indicating the ball in dotted lines. The space that will be in front of the elevation 50 receives the ball so that the ball may be readily removed and placed on the elevation 50 and another shot may be made if the first is not a success. In Fig. 5, the ball 51 is shown emerging from the small end 44 of the channel 42, lifting the deck 47. After the ball has emerged from the conical channel 42, it may strike the tower 60 and displace it, as it is removable. This will add materially to the score. The ball then rolls down the incline and rests finally in one of the pockets heretofore described, which increases the score according to the numerical value of the pocket in which it rests. The rules of the game graphically indicate the value of the various possible shots.

35 The board 10 is pivoted to a base board 61, as at 10', and rests upon rollers 62, so that the board may be rotated for convenience of the players. A drawer 63 is made in the highest part of the game board to 40 contain the balls, flags and other separable portions of the paraphernalia of the apparatus.

45 The game is called "Submarino" and the ball shooting through the channel in the base portion of the board and emerging from the barge, located at a remote point, is in imitation of a torpedo fired by a submarine into a transport.

50 Instead of using the rubber band 54 for the purpose of striking the ball 51, the ball may be struck by the ends of the fingers of the player or by means of a pencil, held between the thumb and finger of one hand and with the finger of the other hand on the 55 end of the pencil and thus the ball may be struck and driven to its destination. Either or any of these means of driving the ball

is permissible and tests the skill of the player.

While I have herein shown and described a single embodiment of my invention, for the purpose of clear disclosure, it is manifest that changes may be made in the arrangement and configuration of the parts within the scope of the appended claims.

Having thus described my invention, what I claim is:

1. A game apparatus comprising a board having an irregular inclined upper surface in imitation of disturbed water, with a plurality of disturbed pockets to receive a ball and having one or more sub-surface openings extending from the outer edge of the board and terminating near the center thereof; an elevated ball support in the outer terminal of each of the openings to support a ball to be fired and a loose cover normally overlying the inner terminal of the respective openings to be removed by the ball in its flight through the opening. 80

2. A game apparatus comprising a board having an irregular inclined upper surface in imitation of disturbed water, with a plurality of distributed pockets, numerically designated, to receive a ball, and having one or more inwardly tapering sub-surface openings converging from the outer edge of the board and terminating near the center thereof; an elevated ball-support in the outer terminal of each of the openings to receive a ball to be fired; a loose cover, normally overlying the inner terminal of each of the openings, to be removed by the ball in its flight through the respective openings, and a resilient impact member for striking the ball to drive it through the opening. 95

3. A game board having an irregular inclined upper surface to represent one or more bodies of water and having a plurality of numerically designated pockets in the surface of the water to receive the ball; a plurality of objects in the center of the board representing sea-going vessels, each having a removable deck; said board having a submarine opening extending from the deck of each vessel to the outer edge of the board and means, at the outer terminal of each said opening, whereby to drive the ball through the surface representing water and in its flight to remove the decks of the respective vessels. 105

In testimony whereof I hereunto subscribe my name.

THOMAS C. P. TRELEAVEN.
